Int. Cl. D7—01

U.S. Cl. D7—5

FIG. 1 is a front elevational view of a combined drinking mug and stand therefor showing my new design;

FIG. 2 is a side elevational view partially in section, the side opposite being a mirror image thereof; and

FIG. 3 is an exploded perspective view thereof, the cover in an open position.

The bottom of the design shown in FIGS. 1-3 is substantially plain and unornamented. The back side, opposite that of FIG. 1, is true football form, and therefore appears exactly as the front in FIG. 1 without the stitching and the finger grip recesses.

I claim:

The ornamental design for a combined drinking mug and stand therefor, as shown and described.
